HANGING LANTERN

Eduard R. Huegel, Brooklyn, N. Y., assignor to Rambusch Decorating Company, New York,
N. Y., a corporation of New York

Application April 1, 1952, Serial No. 19,143

Term of patent 14 years

(Cl. D48—23)

To all whom it may concern:

Be it known that I, Eduard R. Huegel, a citizen of the United States of America and a resident of Borough of Brooklyn, county of Kings, city and State of New York, have invented a new, original, and ornamental Design for a Hanging Lantern, of which the following is a specification, reference being had to the accompanying drawing, forming a part thereof.

In this drawing the single figure is a perspective view of a hanging lantern showing my new design.

I claim:

The ornamental design for a hanging lantern, as shown.

EDUARD R. HUEGEL.
